2,140,633

MEANS FOR DRIVING TUBE DRAWING
BENCHES

Fritz Kocks, Dusseldorf, Germany

Application March 18, 1937. Serial No. 131,710
In Germany March 17, 1936

5 Claims. (Cl. 205—4)

In order to obtain continuous graduation of control of tube drawing benches it has hitherto been customary to equip the electric driving mechanism with an Illgner set. The Illgner set may be compared with the Leonard transformer, which consists of a direct current dynamo ordinarily driven by a three-phase current motor and adapted to feed the actual working motor. This combination forms a transformer. If this combination is provided with a flywheel which serves for receiving current impulses, the transformer is then referred to as an Illgner transformer or set. In view of the fact that the electrical equipment is already more expensive than the remaining portion of the plant, the necessity of using the Illgner set increases the cost of the whole plant out of all proportion. However not only this circumstance but also other disadvantageous features attending the aforesaid electric drive, constitute the reason for regarding the customary arrangements for driving tube drawing benches as still imperfect. Apart from the low efficiency of the Illgner set (about 65—70%), this system calls for considerable skill and care on the part of the operatives in order to adapt the drawing operation to meet the specific working conditions of the Illgner set. Even the design of the drawing bench itself must be modified to suit these peculiarities of the Illgner set, in order to prevent the drawing bench from being affected as the result, for example, of the ever-present contingency of the motor functioning wrongly. Up to the present, this possibility has been taken into consideration by allowing the rack a free run-out beyond its normal end position and arranging at the same time for the rack to move out of gear with the driving pinion and then come to rest. This considerably increases the length of the bench, and thus has an unfavourable effect on the space occupied.

According to the invention the Illgner set is made superfluous, the drive being effected by employing a continuously-running three-phase motor which imparts the forward and return strokes to the rack through a controllable hydraulic gear, the known gear invented by Thoma being preferred.

The new drive provides simple means for maintaining uniform speeds, both for the return and for the working strokes, so that, for example, the working stroke is performed at the rate of about 2 metres per second and the return stroke at about 6 metres per second. The resulting utilization of the speeds according to plan furnishes a large number of finished tubes and therefore a

high degree of efficiency unattainable with the usual inaccurate manual control. Also bearing in mind that the reversing of the direction of movement of the rack is effected much more quickly with hydraulic gear, and more smoothly than in the case of an electric drive of the type hereinbefore referred to, it will be evident that this circumstance also has a beneficial influence on the output. These advantages of the drive also bring others in their train. For example, overstressing of the rack teeth is effectively prevented by the provision, in the hydraulic gear, of a safety or relief valve in the pipe connecting the pump and the actuating unit of the drive. This measure renders superfluous the provision of an over-run for the rack and for simultaneously disengaging it from the driving pinion. Reversing the rack can be effected automatically in very simple manner—for example when the Thoma gear referred to is used—by providing electromagnets and trip contacts, by means of which one or other of the rockable cylinders (or both) are moved beyond their neutral position, from one inclined position into another and at an angle in relation to the driving shaft, the said inclined positions being determined by stops—adjustable if desired—in order to ensure the maintenance of uniformity in the outward and return strokes of the rack.

The new drive also affords in very special manner the possibility of optimum adaptation to particular local conditions, by setting up the pump and the actuating unit of the hydraulic gear separately from each other. This separation is possible because the pump portion and actuating portion of the hydraulic gear are necessarily connected together by only a pressure-supply pipe and a common tank for the liquid (oil). Finally, it is pointed out that in actuating the rack by means of two or more pinions, each connected with an actuating unit of the hydraulic gear, the work may be performed with only one pump unit, common to all. This renders a multiple-pinion drive particularly valuable because it enables the total power to be distributed in equal, or also intentionally different, proportions, between the several pinions, since all the actuating units of the hydraulic system are dependent on a common pressure-supply pipe. This last type of drive is particularly advantageous in the event of the reverse failing to come into action. In such case the rack comes, when running out, out of gear with the last pinion. Since this pinion is no longer exposed to the reaction pressure, the pressure in the delivery pipe of the hydraulic

gear drops and all the oil delivered by the pump passes through the actuating unit allotted to the disengaged, and therefore idling, pinion. Consequently, none of the other pinions can any longer transmit power to the rack, and in this manner the drawing bench is automatically and effectively freed from any excessive stressing.

When the rack is driven by a number of pinions, hydraulic gear may be used comprising a pump unit for each actuating unit, provided all the actuating units be served by a common pressure-pipe.

Several methods of carrying out the invention are diagrammatically illustrated in the accompanying drawings.

Figure 1 is a diagrammatic representation of a tube drawing bench with operating mechanism according to the invention.

Figure 2 is a similar view of a modification, illustrating the use of two pinions for driving the rack of the tube drawing bench.

Figure 3 is a similar view of a further modification.

Figures 4 and 5 are respectively a sectional elevation and a sectional plan of a Thoma gear, as applied to the tube drawing bench driving mechanism.

Referring to Figure 1 of the drawings the three-phase motor 1 actuates the pinion 3 of the rack 4, through hydraulic gearing 2. 5 is the mandrel. 6 and 7 denote solenoids or electromagnets which are connected, in the interior of the gearing 2—for example, of the Thoma type—with the rockable cylinders of the pump and the actuating units. Arranged in the circuits 8 and 9 for the solenoids or electromagnets 6 and 7 are trip switches 10 and 11, actuated by the rack 4 in its opposite end positions. The drawing bench operation is performed by the three-phase motor 1 imparting the working stroke to the rack 4—and with it the mandrel 5—through the hydraulic gear 2. At the end of the working stroke the rack trips on the switch 11, by which means the corresponding circuit is completed or broken. Consequently the armature of the solenoid or electromagnet 7 describes an axial movement and thereby swings the motor cylinder body of the gearing 2 into position for reversing the pinion 3. The return stroke of the rack then follows, at the end of which the rack trips the switch 10, thereby causing movement of the armature of the solenoid or electromagnet 6 and causing, for example, the pump cylinder body of the gearing 2, to swing into neutral position. At the same time the motor cylinder body must swing—as can also be effected automatically by suitable relation of the control circuits—into position for the forward stroke of the rack 4, directly the pump cylinder body has swung back from the neutral position 60 into the working position. So far as the invention is concerned, it is immaterial whether the reversing movements are effected by tilting the two cylinder bodies provided in the Thoma gear, or whether only one of the cylinder bodies is 65 swung into the necessary inclined position.

Figure 2 represents a modification of the construction according to Figure 1 in which the rack 4 is engaged by two pinions 3 and 3'. In this case the hydraulic gear consists of two actuating members 12 and 13, served by a common pump 14. This pump is driven by the motor 1 and connected to the actuating members 12 and 13, as shown. It will be evident that this arrangement ensures exact distribution of motive power between the members 12 and 13, and therefore be-

tween the corresponding pinions 3 and 3'. Should the reversing device according to Figure 1 fail to act, as hereinbefore described, the rack, in over-running an end position, will come out of gear with either the pinion 3 or the pinion 3', for example, the first. In consequence, as hereinbefore described, the hydraulic pressure will only be operative to drive the pinion 3, owing to the low resistance, and the movement of the rack will therefore be arrested.

Figure 3 shows, diagrammatically, the separate arrangement of the pump and actuating units of the hydraulic gear 2. As the result of the two units being connected merely by means of pipes 15, the pump unit and the motor can be set up in any convenient place. The manner in which the 2-pinion drive can be arranged in this instance is indicated by dotted lines in Figure 3.

A suitable form of the Thoma drive is illustrated in Figures 4 and 5 and comprises a casing 16 to one end of which the motor 1 is connected by a flange, the motor being a three-phase motor and serving to drive a shaft 17 extending within the casing 16, which shaft receives at the end the spherical ball-like ends of connecting rods 18 which directly drive, also through ball-like ends, pistons 19 which respectively reciprocate in the cylindrical bores in a cylinder body 20. The rotary movement of the driving shaft 17 is transmitted by way of a coupling link 21 with universal joints to a stub spindle or axle 22 upon which the cylinder body 20 is fixedly mounted. The said spindle or axle 22 is mounted as in a counter-bearing, in a valve disc 23 which is applied against the outer end of the cylinder body 20 and forms the end of a casing 24 for the cylinder body, which casing is mounted on fixed pivots 25 disposed in the plane of the end of the driving shaft 17 and permitting it to rock in opposite directions. This movement is effected by means of the electromagnet or solenoid 6 which may be mounted on the upper wall of the casing 16. If the rocking cylinder body casing or frame 24 is inclined relatively to the driving shaft 17 all the pistons 19 reciprocate when the driving shaft is rotated. The travel of the pistons is in this connection determined by the inclination of the rocking casing 24. If the casing is swung into the horizontal position there is no reciprocation of the pistons 19. The casing 16 is provided to contain a liquid, such as oil, and if the cylinder body casing 24 is connected with a dip pipe 26 immersed in the liquid and leading by a passage 27 to the valve surface of the valve disc 23, the cylinder body and the pistons therein when inclined and rotated will act as a pump. A similar cylinder body casing 28 and cylinder body 29 is similarly assembled in relation to the driven shaft 30 provided at the opposite side of the casing 16. This shaft carries the pinion 3. The delivery side of the valve disc 23 of the first cylinder body casing 24 is coupled as by a conduit 31 with the inlet side of the second cylinder body casing 24 so that the liquid forced therein is caused to effect the reciprocation of the pistons 32 in the second cylinder body 29 before being discharged to the liquid in the casing 16 by way of the dip pipe 33. In this manner the driven shaft is caused to rotate. The rocking of the cylinder body casing 28 is effected by the electromagnet 7 or solenoid 1. The peculiarity of this Thoma drive consists in the fact that by rocking the cylinder body of the pump and that of the motor the speed of rotation and the work output of the device can be very effectively regulated.

In the arrangement according to the invention with the motor running at a constant speed the working speed of the drawing bench can be smoothly graduated, and the direction of stroke reversed, in contrast to the existing methods of driving in which the motor actuating the rack gear was itself controlled in respect of speed.

I claim:

1. A tube drawing bench having the mandrel reciprocated by a rack with which is engaged a pinion driven by a prime mover, comprising a constant speed motor serving as the prime mover and a variable hydraulic transmission gear interposed between the motor and the rack pinion for varying the speed and direction of drive of the mandrel, the said gear comprising pumps and actuating units that are independent one of the other, and fluid-containing means for completing the fluid circuit between the pumps and the actuating units, control of the operation of the pumps and actuating units being effected automatically from the reciprocating elements of the tube drawing bench.

2. A tube drawing bench according to claim 1, in which the pumps or the actuating units of the hydraulic transmission gear are adjustable of position for variation of the effort produced, and means for effecting such adjustment of position

under control of the reciprocating elements of the tube drawing bench.

3. A tube drawing bench according to claim 1, in which the pumps and the actuating units of the hydraulic transmission gear are adjustable of 5 position for variation of the effort produced, and means for effecting such adjustment of position under control of the reciprocating elements of the tube drawing bench.

4. A tube drawing bench having the mandrel 10 reciprocated by a rack with which are engaged a multiplicity of pinions, a constant speed motor, a variable hydraulic transmission gear, comprising pumps rotated by the motor and groups of actuating units in number corresponding to the number of pinions, each group of actuating units being specific to one pinion, fluid-containing means common to the pumps and the actuating units, and means for varying the speed and direction of 15 the drive imparted to the said pinions by the said groups of actuating units, said means being controlled by the reciprocating elements of the tube drawing bench.

5. A tube drawing bench according to claim 4, wherein a single pump unit of the variable hy- 25 drdraulic transmission gear operates a number of groups of actuating units.

FRITZ KOCKS.
